Primary Examiner — Mimosa De(74) *Attorney, Agent, or Firm* — Karish & Bjorgum, PC(57) **CLAIM**

The ornamental design for a chair, as shown and described.

DESCRIPTION

FIG. 1 is a perspective view of the chair with a solid seat and arms.

FIG. 2 is a top view of the chair with a solid seat and arms.

FIG. 3 is a front view of the chair with a solid seat and arms.

FIG. 4 is a left side view of the chair with a solid seat, the right side view being a mirror image of the left side view and arms; and,

FIG. 5 is a back view of the chair with a solid seat and arms. The bottom view is not part of the design. The chair legs have an organic wood grain appearance.
